STORM WINDOW STRUCTURE

Raleigh R. Martin, Anderson, Ind.

Application October 10, 1945, Serial No. 621,449

9 Claims. (Cl. 160—90)

1

This invention relates to a storm window structure.

The chief object of this invention is to provide a storm window with a minimum number of parts and which may be screen equipped and which can be relatively permanently mounted exteriorly of a conventional guillotine or oppositely opening French single or double window construction.

One chief feature of the present invention resides in the frame thereof, which is of integral multiple channel type that slidably supports glass or like sheets devoid of framing and which is fitted into the frame of a conventional window outwardly of the outside stop rail thereof.

Another chief feature of the invention resides in providing a movable screen slidably mounted in the said frame and which detachably mounts a screen element permitting screen removal, etc., when desired.

A further feature of the invention resides in the several means provided to hold the screen in elevated position in the frame, and either or both of the two glasses.

Still a further feature of the invention resides in the provision of means for holding partially elevated the so-called lower pane.

Still another feature of the invention resides in the combination hand grip and ventilator structure.

Other objects and features of the invention will be set forth more fully hereinafter.

The full nature of the invention will be understood from the accompanying drawings and the following description and claims:

In the drawings Fig. 1 is a front view of the left hand portion of a storm window embodying the invention.

Fig. 2 is a rear view of the same portion of the window.

Fig. 3 is a rear view of the lower right hand corner of the window, the screen thereof having been elevated, and more particularly of the combination hand grip and ventilator structure.

Fig. 4 is a vertical sectional view through the storm window mounted in a conventional window frame.

Fig. 5 is a perspective view of a portion of frame bottom stock.

Fig. 6 is a similar view of a portion of frame side and top stock.

In Fig. 4 of the drawings 10 indicates a portion (and the top) of a conventional window frame, 11 the sill, 12 the outer stop rail and 13 the facing plate, usually a 1 x 4.

The storm window, see Fig. 1, comprises a frame

2

having two sides 14, a top 15 and bottom 16, all rigidly secured together. The top and sides are substantially identical and each includes an outwardly directed integral covering flange 18 apertured at 19 to take screw 20 and the like by which the storm window frame, when nested in the window opening in the conventional window frame and abutting stop 12 thereof, is secured to the face plate portions 13 of that frame. The mitered corners may be suitably secured together and masked by the corner plates 17.

Obviously, the present invention can be externally applied and relatively permanently secured to any inwardly opening or vertically slidable window structure without interference to the normal operation of the latter. For glass replacement, when necessary, one side may be detachably secured to the top 15 and bottom 16, although this requires demounting and remounting of the storm window.

Coplaner with flange 18, see Figs. 4 and 6, is the inwardly directed outer flange 21 and projecting laterally of the same is the web or base 22. Parallel to flange 21 is a thicker flange 23 and 25 parallel thereto is another flange 25 forming, respectively, the parallel grooves 24 and 26 for the accommodation of the glass or like panes 27 and 28, respectively. Adjacent flange 25 and spaced therefrom and parallel thereto is an inner flange 29 forming groove 30 for screen frame accommodation.

Extending across the frame at the bottom is bottom 16. While the two sides 14 and top 15 are as previously described, bottom 16 includes a dual and oppositely directed U-shaped sectioned structure providing bearing flange 31, sill surface 32, flange 33 and base or web 34 with inner flange 35 parallel to flange 33.

Adjacent flange 35 is parallel flange 36 and spaced therefrom the width of groove 30 and forming the groove 37. The spacing between flanges 33 and 36 corresponds to that of groove 26 but herein an intermediate flange 38 is provided forming two grooves 39 and 40 for a purpose hereinafter to be described.

When pane 27 is seated in the top groove 24 and pane 28 is operatively associated with multiple grooves 39 and 40, as hereinafter described, the panes at their adjacent edges lap each other as illustrated most clearly in Fig. 4. At this overlapping position there is interposed a cross-bar closure member 41 suitably secured at opposite ends to the portions 23 of sides 14 as indicated at 42 in Fig. 4.

Grooves 37, 39 and 40 may each have a drain-

age hole which registers with an inverted V slot connecting same for draining any moisture from the window structure.

Pivotedly supported by said cross-bar member 41 and for projection and retraction purposes, as it were, are the angle members 43 and 44. Members 44, when projected as illustrated in Fig. 4, engage the lower edge of pane 27 and retain the outer upper pane in elevated position. Members 43, when reversely projected following inner lower pane 28 elevation to its highest position, similarly retain same in that position.

To prevent outer pane 27 engaging bottom portion 32, there may be provided in the opposed grooves 24 permanent stops 45, see Fig. 4, and same are positioned above bottom 16 a sufficient distance for the fingers to be passed thereunder for pane elevation purposes. If desired, the several channels or grooves may be provided with a suitable adhesive and flock addition as indicated at 24' in the top of Fig. 4 for silencing (anti-rattling) and sealing purposes.

Reference will now be had to the lower portions of Figs. 1, 2 and 4 and Fig. 3. Therein is disclosed a plate portion 46 provided at the top and bottom with outwardly opening grooves or channels 47 and 48 respectively, the former seating and being suitably secured to the lower edge of lower inner pane 28 as illustrated and so as to constitute a portion of the lower pane structure. The lower groove 48 is adapted to receive flange 38 when the structure is lowered. Members 43 engage the lower edges of plate 46 when fully elevated to hold in elevated position this pane structure.

Plate 46 is provided with a longitudinally directed groove or recess 49 and projecting into same are headed pins 50 carried by the plate 46. Slidable in said recess is plate 51 having pin spaced elongated aligned slots 52. Plate 46 in its intermediate portion is provided with a suitable number of equally spaced openings 53 and plate 51 is provided with a similar number of openings 54. When the openings register, air circulation through the lower pane structure is obtained and this circulation is regulated by the degree of registration effected. When no circulation is desired, the holes are positioned for blocking by the two plates. To facilitate sliding of plate 51 relative to plate 46 the former may be medianly serrated as at 55, see Fig. 3.

Reference will now be had to the lower half of Figs. 1, 2 and 4. The screen structure includes an outer frame and an inner frame, the latter being detachably carried by the former and mounting a screen closure, the outer frame being slidable in channels 30 and seatable when elevated in the top groove 30 and when lowered being seated in bottom groove 37.

In Fig. 4 such structure is most clearly illustrated. Therein 56 indicates a bronze, copper or other suitable material screen stretched across an open rectangular inner frame 57 having inwardly opening peripheral channel 58 terminating in a laterally directed lapping flange 59. A U-shaped resilient retainer 60 frictionally held in the channel 58 retains the screen ends against escape. At the corner and seated in the grooves 58 are the angular connectors 61.

The outer frame, slidable in the window frame grooves 30, comprises the open rectangular structure 62 reenforced by corner angle plates 63. The former is lapped by inner frame flanges 59 and the angle pins 64 or other suitable means detachably secures the inner screen structure in

and upon the outer screen frame, so that the inner screen structure may be removed and replaced at will. The pins 64 may also be used as means for raising and lowering the screen.

Whenever desired, the total screen structure may be retained in elevated position. The means for so doing comprises a supporting bracket or strap 65 carried by a side frame member 14, see Fig. 2. Said strap is socketed at 66, see Fig. 4, and slidably therein is plunger 67 reduced at 68 to form a stem that projects beyond the socket through end opening 69 therein. The outer end of said stem mounts head 70. A coil spring 71 in the socket and enveloping the stem normally constrains the plunger 67 outwardly. When the screen is in the lowered position the plunger 67 projects into a registering aperture in the upper member of the screen frame, and acts as a locking means. When the screen is elevated the plunger projects below the screen and the latter rests thereon.

While the invention has been illustrated and described in great detail in the drawings and foregoing description, the same is to be considered as illustrative and not restrictive in character.

The several modifications described herein, as well as others which will readily suggest themselves to persons skilled in the art, all are considered to be within the broad scope of the invention, reference being had to the appended claims.

The invention claimed is:

1. A storm window structure comprised of top, bottom and two side members, each of a rigid non-wood material and having confronting channels formed therein, glass panes slidable in the channels, an intermediate cross-bar member between the side members and lapped by the panes, and a plurality of means carried by the cross-bar member and selectively projectible into positions lying in the planes of movement of the panes for selectively retaining said panes in elevated position.

2. A storm window structure as defined by claim 1 wherein a plate is associated with the lower edge of one of the panes and coextensive therewith and is seated in the bottom channel when the plate is in lowermost position.

3. A storm window structure as defined by claim 1 wherein a plate is associated with the lower edge of one of the panes and is coextensive therewith and is seated in the bottom channel when the plate is in lowermost position, said plate having a pane seating upper groove, and a flange seating lower groove, the bottom channel including an upwardly projecting flange seatable in the last mentioned groove.

4. A storm window structure as defined by claim 1 wherein a lower plate is associated with the lower edge of one of the panes and is coextensive with the same and seated at opposite ends in a pair of confronting side channels, the lower edge of the plate seating in the bottom channel when in lowermost position, said plate having a pane seating grooved upper edge and a plurality of spaced openings therethrough, another plate slidably supported on the first plate and of a lesser length and having correspondingly spaced openings therethrough for air circulation and pane raising purposes.

5. A storm window structure as defined by claim 1 wherein a lower plate is associated with the lower edge of one of the panes and is coextensive with the same and seated at opposite

ends in a pair of confronting side channels, the lower edge of the plate seating in the bottom channel when in lowermost position, said plate having a pane seating grooved upper edge and a plurality of spaced openings therethrough, another plate slidably supported on the first plate and of a lesser length and having correspondingly spaced openings therethrough for air circulation and pane raising purposes, and aligned pin and elongated slot connections between said plates. 10

6. A storm window structure as defined by claim 1 wherein a lower plate is associated with the lower edge of one of the panes and is coextensive with the same and seated at opposite ends in a pair of confronting side channels, the lower edge of the plate seating in the bottom channel when in lowermost position, said plate having a pane seating grooved upper edge and a plurality of spaced openings therethrough, another plate slidably supported on the first plate and of a lesser length and having correspondingly spaced openings therethrough for air circulation and pane raising purposes, and parallel disposed finger engageable means formed on the second plate between two of said spaced openings therein for facilitating plate sliding. 25

7. A storm window structure as defined by claim 1 wherein a lower plate is associated with the lower edge of one of the panes and is coextensive with the same and seated at opposite ends in a pair of confronting side channels, the lower edge of the plate seating in the bottom channel when in lowermost position, said plate having a pane seating grooved upper edge and a plurality of spaced openings therethrough, another plate slidably supported on the first plate and of a lesser length and having correspondingly spaced openings therethrough for air circulation and pane raising purposes, and aligned pin and elongated slot connections between said plates, and parallel disposed finger engageable means formed on the second plate between two of said spaced openings therein for facilitating plate sliding. 40

8. A screen structure comprising an open rectangular frame, an inner frame having an outwardly directed flange lapping the first frame, means detachably securing said frames together, said inner frame having an opening defining portion extending toward and nesting in the opening in the first frame, said portion on its inner face having a groove therein and disposed

about the inner frame opening, but spaced from the faces of said inner frame and screening closing the inner frame opening and having its edges seated and suitably retained in the groove. 5

9. A storm window structure as defined by claim 1 wherein each of the members includes an additional channel, a metallic frame screen slideable therein, and means carried by one of the members and movable into blocking position for screen retention in elevated position, said screen comprising an open rectangular frame, an inner frame having an outwardly directed flange lapping the first frame, means detachably securing said frames together, said inner frame having an opening defining portion extending toward and nesting in the opening in the first frame, said portion on its inner face having a groove therein and disposed about but spaced from the inner frame opening, and screening closing the inner frame opening and having its edges seated and suitably retained in the groove. 15 20
